T. L. STURTEVANT.
WATER COOLED VALVE FOR INTERNAL COMBUSTION ENGINES.
APPLICATION FILED MAY 21, 1914.

Patented June 13, 1916.

Inventor:

Thomas L. Sturtevant,

UNITED STATES PATENT OFFICE.

THOMAS LEGGETT STURTEVANT, OF QUINCY, MASSACHUSETTS, ASSIGNOR TO
STURTEVANT MILL COMPANY, A CORPORATION OF MAINE.

WATER-COOLED VALVE FOR INTERNAL-COMBUSTION ENGINES.

1 186.860

Specification of Letters Patent. Patented June 13, 1916.

Application filed May 21, 1914. Serial No. 340,072.

To all whom it may concern:

Be it known that I, THOMAS L. STURTEVANT, a citizen of the United States, residing at Quincy, in the county of Norfolk and State of Massachusetts, have invented or discovered certain new and useful Improvements in Water-Cooled Valves for Internal-Combustion Engines, of which the following is a specification, reference being had therein to the accompanying drawing, which is interposed a coil spring 20 which serves to press the valve 16 to its seat 13. The nut 18 is recessed peripherally for the reception of a spanner by which it may be turned for the purpose of regulating the stress of said spring, and the top or anvil portion of the cap 16 is formed square or polygonal for the reception of a wrench in screwing or unscrewing said cap. The valve 16 has

10 had thereto the accompanying drawing.
This invention relates to water cooled
valves for internal combustion engines, and
has for its object to provide a valve of this
character which is of simple construction,
15 which is effective in operation, and which
embodies certain features of convenience
for regulating the operation of the valve.

In the accompanying drawing Figure 1 is a vertical sectional view of the valve and valve cage embodying the present invention. Fig. 2 is a detail view illustrating a modified form of flexible tube connection by which water may be supplied to the hollow valve stem from the water jacket of the engine cylinder. Figs. 3 and 4 are detail views of a preferred form of cap.

views of a preferred form of the invention. Referring to the drawings, 12 denotes a cage provided with a valve seat 13, and with an extended boss 14 forming a sheath or tube which serves as a vertical bearing for a hollow valve stem 15 to which is attached a hollow valve head 16, or the said valve head may, if desired, be cast integral with said hollow stem. The boss or tube 14 is preferably formed integral with the cage 12, but may be formed separate therefrom and be fixed thereto. The cage 12 is adapted to be removably fitted or attached to the cylinder of an internal combustion engine, as, for example, the well-known Murray & Tregurtha marine engine, for which this invention is well adapted.

To the upper end of the hollow sleeve stem 15 is attached a hollow cap 17 the sleeve portion of which is screw threaded to said valve stem and the top of which cap serves as an anvil to be engaged by a valve operating device or lever. The sleeve portion of said cap 17 is screw threaded externally for the reception of a nut 18 be-

tween which and the top 19 of the cage 12 is interposed a coil spring 20 which serves to press the valve 16 to its seat 13. The nut 18 is recessed peripherally for the reception of a spanner by which it may be turned 55 for the purpose of regulating the stress of said spring, and the top or anvil portion of the cap 17 is formed square or polygonal for the reception of a wrench in screwing or unscrewing said cap. The valve 16 has 60 a screw threaded connection, by means of a sleeve portion 21, with the lower end of the hollow valve stem, said sleeve portion 21 being formed square or polygonal for the reception of a wrench by which the 65 valve may be held when the hollow cap 17 is to be screwed or unscrewed.

The hollow cap 17 is provided with an inlet pipe or nipple 22 communicating with a pipe 22^a extending downward through the hollow valve stem 15 and opening at its lower end into the chamber of the hollow valve 16, the said inlet pipe or nipple 22 being preferably connected by a flexible tube 23 with the top portion of the water jacket 24 of the engine cylinder, so that the valve may be cooled by water taken from the circulation in the water jacket. The pipe 22^a is preferably smaller in diameter than the diameter of the bore of the hollow valve 80 stem 15 so that water flowing in one direction through said pipe may flow in the opposite direction in said stem outside of said pipe; and the hollow cap 17 is provided with a discharge pipe or nipple 25 through 85 which the cooling water escapes from the hollow valve stem. This discharge pipe and nipple may, if desired, have a flexible connection with another valve stem, so that the several valves of an engine may be connected in series, thereby enabling them all to be cooled by water flowing from one to another; or the discharge pipe or nipple may be otherwise connected to any suitable point of discharge. The circulation of 90 water through the valve will preferably be effected by the water pressure of the circulating pump of the water-cooling system of the engine, but it will be understood that the cooling water may be supplied under 95 100

pressure to the inlet to the valve stem from an independent force pump or pressure system.

Mounted on the cage 12 is an oil pipe 26 which connects a pressure oil cup 27 with a duct 28 formed in said cage, so that the bearing for the valve stem, afforded by the boss or sheath 14, may be properly lubricated, the pressure oil cup being connected 10 with any suitable oil pressure supply.

Instead of connecting the inlet pipe or nipple 22 with the water jacket of an engine cylinder by means of a flexible tube 23 such connection may be made by a pipe 29 having suitable packed joints, at 30, as will be understood from the detail view Fig. 2, and which jointed pipe affords such a flexible connection as will admit of an uninterrupted circulation when the valve is in operation.

From the foregoing it will be apparent that the parts comprising the present improved water cooled valve construction are all carried by the cage 12 which is adapted 25 to be removably placed in or on the engine cylinder, so that all of said parts may be supplied to or removed from the engine cylinder as a unit; while the construction is such that the valve stem may be properly lubricated and the pressure of the valve spring conveniently adjusted, according to requirements. Of course it will be understood that when the valve is to be removed from the engine the flexible tube connecting the hollow 30 valve stem with the water jacket of the cylinder will be disconnected.

Instead of making the inlet and outlet pipes or nipples separate from the hollow cap 17 and screwing them into or brazing them to said cap, as shown in Fig. 1, the said pipes or nipples 22^a and 25^a, respectively, may be cast integral with said hollow cap, as shown in Figs. 3 and 4, thereby avoiding joints which might leak, and reducing 45 the cost of construction. In this form of cap the circulation pipe 22^a is preferably attached to the cap 17 by being screwed into said cap, as shown in Fig. 4.

By obtaining the water supply of the 50 water cooled valve from the top portion of the water jacket of the engine cylinder the formation of a steam pocket in the said water jacket is avoided. This is an important matter, in that the bubbles of air or 55 steam, which are likely to form so-called "pockets" in the top parts of the water jackets of engine cylinders, are withdrawn, and which pockets are liable to hold the circulating water away from the parts to be cooled, so that by thus taking the cooling water from the top part of the water jacket of the engine and forcing the same under pressure through a closed conduit between the engine cylinder water jacket and said

valve stem and valve head a proper cooling 65 of the hollow valve head is reliably insured.

Having thus described my invention I claim and desire to secure by Letters Patent:—

1. A water cooled valve device, for internal combustion engines, comprising a cage 70 affording a valve seat, a hollow valve fitted to said seat, a hollow stem to one end of which said valve is attached, a hollow cap removably attached to the other end of said stem concentric therewith and provided with inlet and discharge pipes or nipples, an inlet pipe extending from said inlet nipple to the chamber of said hollow valve, said pipe being smaller in diameter than the bore of 75 said hollow stem, a boss or tube fixed with relation to said cage, a valve-closing spring disposed between said cage and said cap and encircling said boss or tube, and an adjustable nut on said cap for regulating the tension of said spring.

2. A water cooled valve device, for internal combustion engines, comprising a cage 80 affording a valve seat, a hollow valve fitted to said seat, a hollow stem to one end of which said valve is attached, a concentrically mounted hollow cap removably attached to the other end of said stem and provided with inlet and discharge pipes or nipples, a pipe extending from said inlet 85 nipple to the chamber of said hollow valve, said pipe being smaller in diameter than the bore of said hollow stem, a boss or tube fixed with relation to said cage and affording a bearing for said valve stem, a valve-closing 90 spring arranged between said cage and said cap and encircling said boss or tube, an adjustable nut on said cap for regulating the tension of said spring, a pressure oil cup, 95 and means for supplying oil from said cup to the bearing of said valve stem.

3. A water cooled valve device for internal combustion engines, comprising a valve seat, a hollow valve fitting said seat, a hollow valve stem, said hollow valve being provided with a sleeve portion having a screw-threaded connection with the lower end of said valve stem, said sleeve portion being formed square or polygonal for the reception of a wrench, and a hollow removable 110 cap having a screw-threaded connection with the upper end of said valve stem, said cap having a portion also formed square or polygonal for the reception of a wrench, whereby the said cap may be conveniently 115 removed, when desired, and the valve stem to be held from turning movements by a wrench to be applied to the sleeve portion of the valve.

4. In a water cooled valve construction, 120 the combination with a hollow valve and hollow valve stem, of an engine cylinder water jacket, a closed conduit between the

top part of said water jacket and the said valve, whereby the latter may be cooled by water forced under pressure directly from the top part of said water jacket, an extended bearing for said valve stem, and means for forcing a lubricant into said bearing.

In testimony whereof I affix my signature, in presence of two witnesses.

THOMAS LEGGETT STURTEVANT.
